DESIGN FOR A BUCKLE OR SIMILAR ARTICLE

Malcolm R. Weill, New York, N. Y.

Application December 14, 1940, Serial No. 97,310

Term of patent 3½ years

To all whom it may concern:

Be it known that I, Malcolm R. Weill, a citizen of the United States of America, residing in New York city, county of New York, and State of New York, have invented a new, original, and ornamental Design for a Buckle or Similar Article, of which the following is a specification, reference being had to the accompanying drawing, forming part thereof, wherein,

I claim:

The ornamental design for a buckle or similar article, substantially as shown.

MALCOLM R. WEILL.
